FIG. 1

FIG.2

FIG.3

FIG.4

FIG.5

FIG.6

FIG.7

FIGURE 1 is a perspective view of my design for a portable phonograph cabinet shown in an open or playing position;

FIGURE 2 is a side elevational view thereof with the cabinet in the open position;

FIGURE 3 is a plan view as seen from line 3—3 of FIGURE 2;

FIGURE 4 is a front perspective view of my design shown in a closed or carrying position; and

FIGURES 5, 6 and 7 are side, rear and bottom views respectively of the portable phonograph cabinet in its closed position.

The dominant features of my design reside in those portions of the drawing shown by means of full lines.

I claim:

The ornamental design for a portable phonograph cabinet, substantially as shown and described.
